UNITED STATES PATENT OFFICE

2,489,283

BIPOD

John C. Garand, Springfield, Mass., assignor to
the United States of America as represented by
the Secretary of War

Application September 19, 1947, Serial No. 775,092

8 Claims. (Cl. 42—94)

(Granted under the act of March 3, 1883, as
amended April 30, 1928; 370 O. G. 757)

1

The invention described herein may be manufactured and used by or for the Government for governmental purposes without the payment of any royalty thereon.

This invention relates to a support for a firearm and more particularly to an improved light bipod rest especially adapted for use with rifles and light machine guns.

The exigencies of modern combat demand that bipods be securely locked in both their operating and stowed positions and yet be adapted for a rapid change from one position to the other. Such requirements have been accomplished in the art but involve undesirable and time-consuming adjustment. Moreover the presence of such features adds considerably to the weight of the entire bipod and decreases the simplicity of construction.

It is therefore an object of this invention to provide a simple, light-weight yet sturdily constructed firearm bipod having positive automatic means for locking such bipod in either the operating or stowed positions.

It is also essential that the vertical height of bipods be readily adjustable and securely locked in all positions of adjustment. Prior art height-adjusting means are too often disturbed by the vibration encountered in the continued firing of automatic weapons.

Accordingly, it is a further object of this invention to provide a firearm bipod having height-adjusting means arranged to automatically lock in the position selected.

It is still a further object of this invention to provide a bipod adapted for rapid removal from a firearm or equally rapid assembly thereto regardless of the position of the bipod legs at that time.

The specific nature of the invention as well as other objects and advantages thereof will clearly appear from a description of a preferred embodiment as shown in the accompanying drawings in which:

Fig. 1 is a side elevational view of the bipod of this invention shown in the operating and stowed positions with respect to a firearm.

Fig. 2 is an enlarged sectionalized view of the mounting bracket assembled to the locking bracket.

Fig. 3 is a rear elevational view of the bipod shown in the operating position with respect to the firearm.

Fig. 4 is an enlarged rear end sectionalized view of one of the feet of the bipod legs.

2

Fig. 5 is an enlarged fragmentary view in section of the sleeve.

Fig. 6 is an enlarged partial side elevational view of the bipod.

Fig. 7 is an enlarged detail plan view of the latch.

Fig. 8 is an enlarged fragmentary front view of the intersection of the bipod legs showing the position of the cam slots when the legs are spread apart in the operative position.

Fig. 9 is a view similar to Fig. 8 but taken when the legs are folded together as in the stowed position.

Fig. 10 is a perspective view of the connecting member.

As shown in Figs. 1, 2 and 6, the bipod of this invention is mounted to the conventional bayonet lug 10 found in the U. S. rifle, cal. .30, M1 on the underside of the gas cylinder 11 which is in turn secured beneath the firearm barrel 12. However, it should be understood that this bipod is adapted for use with any rifle or light machine gun intended to be fired in the prone position. If the weapon is not provided with a bayonet lug, any similar lug or bracket which depends from the barrel or other convenient portion of the firearm may be used to mount the bipod thereon.

In any event, there is here provided a mounting bracket 13 having an undercut groove 14 therein and a latch 15 associated with mounting bracket 13 and arranged to be biased upwardly by a torsion spring 16 so as to project in front of the mouth of groove 14. The top surface of mounting bracket 13 projects slightly beyond the rear face thereof and thereby serves to limit the upward movement of latch 15. Thus when groove 14 surrounds bayonet lug 10, as shown in Fig. 6, latch 15 secures mounting bracket 13 to the firearm until such latch is depressed downwardly against the bias of spring 16. It should be also noted that mounting bracket 13 is adapted to be latched or unlatched from bayonet lug 10 regardless of the position of the remainder of the bipod. The rear face of mounting bracket 13 is provided with a depending integral lug 17 having a bifurcated portion 18 at the bottom thereof.

A locking bracket 19 is pivotally secured to mounting bracket 13 by a pin 20 for movement in a plane at right angles to the longitudinal axis of the firearm. A shoulder 21 is provided on locking bracket 19 and arranged to contact the underside of mounting bracket 13 so as to limit the

extent to which the former, and consequently the entire bipod, can be transversely pivoted with respect to the firearm. Such construction, however, allows sufficient transverse pivotal movement of the firearm for correcting any cant in the line of sight thereof which may occur when the bipod is standing on uneven terrain. Locking bracket 19 is bifurcated as shown at 22 in Fig. 1. A transverse pin 29 is provided in bracket 19 vertically below shoulder 21 and passing through bifurcation 22 for a purpose to be later described. A forward transverse notch 23 vertically below pin 29 and a transverse notch 24 rearwardly disposed from notch 23 are provided on bracket 19 as well as a sloping cam surface 25 and a rearwardly extending projection 26.

A connecting member 27 is provided with a substantially rectangular stem portion 28, the upper end of which fits into bifurcation 22 and is pivotally joined to locking bracket 19 by pin 29 so as to permit swinging movement of connecting member 27 in a plane parallel to the longitudinal axis of the firearm. Integral with stem portion 28 there is provided a cylindrical base portion 30, the top of which seats a coil spring 31 mounted to surround the adjacent section of stem portion 28. Base portion 30 is bifurcated as shown at 32 in Fig. 10 and a slot 33 extends through base portion 30 so as to intersect bifurcation 32 at right angles.

A sleeve member 34 is slidably mounted over connecting member 27 by means of a pin 35 extending through slot 33. The top edge of sleeve member 34 is bent inwardly at right angles to form a rim 36. When sleeve member 34 is assembled to connecting member 27, spring 31 is compressed between the top of base portion 30 and the underside of rim 36 and thereby normally urges sleeve 34 upwardly with respect to connecting member 27. Extending upwardly from rim 36 are a pair of detents 37 arranged to project into notches 23 and 24. The outer surface of sleeve member 34 is grooved as shown at 38 to provide a gripping surface for manual movement of such member.

A pair of bipod legs 39 are pivotally secured within bifurcated portion 32 of connecting member 27 by a pin 40 fixedly secured as by staking or the like through the lower end of base portion 30. Legs 39 are thereby arranged to pivot toward and away from one another in a plane at right angles to the longitudinal axis of the firearm to which the bipod is mounted. At the top portion of each leg 39 there is provided a V-shaped cam slot 41 having one arm portion 42 relatively longer than the other arm portion 43. When legs 39 are pivotally mounted to base portion 30, cam slots 41 face in opposite directions but nevertheless are aligned sufficiently to provide openings through which pin 35 extends, as shown in Figs. 3 and 6. The extreme end of each of longer arm portions 42 is slightly enlarged as shown at 44.

Each bipod leg 39 terminates at its lower end in an arcuately-formed spade-like foot 45 having a bent-over portion 46 extending downwardly with respect to the plane surface of foot 45. Legs 39 are preferably stamped or pressed from sheet stock as a single unit. Such method of fabrication not only assures a light weight, sturdy construction but also lends itself to simplicity in manufacture.

When bipod legs 39 are in the spread apart and operative position, the enlarged ends 44 of slot portions 42 are aligned as shown in Fig. 8 to form an opening for the seating therein of pin 35.

Spring 31 maintains such arrangement and thereby prevents accidental displacement of legs 39 from such position. At the same time, detents 37 are engaged in either notch 23 or notch 24 to lock the bipod in the operative position. However, when legs 39 are forced together, cam slots 41 pivot to align the shorter slot portions 43 into a unitary track. Pin 35 is therefore cammed downwardly with respect to locking bracket 19 by the diverging movement of longer slot portions 42 so as to ride along shorter slot portions 43. This downward movement of pin 35 causes sleeve 34 to retract detents 37 out of engagement with notch 23 or 24 thereby permitting swinging movement of legs 39 in a plane parallel to the longitudinal axis of the firearm. When legs 39 are released from being grasped, the bias of spring 31 forces sleeve 34 and thereby pin 35 upwardly and pivots cam slots 41 so that pin 35 seats in the aligned enlarged ends 44 of slot portions 42.

To stow the bipod, legs 39 are folded together as explained above and are swung rearwardly until detents 37 are engaged behind projections 26. During such movement, detents 37 ride along sloping cam surface 25 and, as a result, sleeve member 34 and consequently pin 35 are cammed downwardly to compress spring 31. Sleeve member 34 is maintained in such position by the abutment of detents 37 against the rear face of locking bracket 19. It can thus be seen that legs 39 are maintained in a locked and stowed position and can only be released by the manual retraction of sleeve member 34 from behind projections 26. Furthermore, in such stowed position, the stem portion 28 of connecting member 27 is engaged between the bifurcated portion 18 of lug 17. As a result, mounting bracket 13 is rigidly locked against movement with respect to the rest of the bipod.

When sleeve member 34 is manually retracted and the bipod legs 39 pushed forwardly, the bias of spring 31 will cause detents 37 to ride along cam surface 25 until aligned with rearward transverse notch 24 whereupon detents 37 automatically engage therein and lock the bipod in this first operating position.

Although legs 39 are cammed apart during such movement, the longitudinal axis thereof is angularly disposed with respect to the longitudinal axis 50 of the firearm. To increase the vertical elevation of the firearm, sleeve member 34 must again be manually retracted and legs 39 swung forwardly so that detents 37 will engage forward transverse notch 23. In such position, legs 39 will be disposed substantially at right angles to the longitudinal axis of the firearm and thereby provide the maximum vertical height in which the bipod can support the firearm. The forward swinging of connecting member 27 and thereby sleeve member 34 is limited by the contact of the top of stem portion 28 with the underside of the bifurcated portion 22 of locking bracket 19.

It should be noted that when sleeve member 34 has been pivoted so that detents 37 engage notch 24, stem portion 28 of connecting member 27 is no longer engaged in the bifurcated portion 18 of mounting bracket lug 17. Accordingly, mounting bracket 13 and thereby the firearm can be transversely pivoted to correct any cant in the line of sight.

The construction of the bipod is also such that sleeve member 34 can be retracted by merely pressing legs 39 together from the spread apart 75 operative position. This movement causes cam

slots 41 to cam pin 35 and thereby sleeve member 34 downwardly. Thus, except for the manual retraction of sleeve member 34 required to disengage detents 37 from behind projections 26, the bipod can be locked in either of its two operating positions or the stowed position. It can also be retracted merely by moving legs 39 as explained above.

Thus it can be readily seen that there is here provided a simple, light-weight, sturdy bipod which can be rapidly adjusted between a stowed position and either of two operating positions and be automatically locked in each of such positions.

I claim:

1. The combination with a firearm of a bipod support comprising, a latching member arranged to be removably mounted on a projecting lug of the firearm, a locking bracket pivotally mounted on said latching member for transverse movement with respect to the longitudinal axis of the firearm, a connecting member pivotally mounted at one end to said locking bracket for swinging movement between an operative position substantially at right angles to the longitudinal axis of the firearm to a stowed position substantially parallel therewith, a pair of legs pivotally mounted on said connecting member for movement toward and away from one another in a plane substantially at right angles to the longitudinal axis of the firearm, spring biased detent means slidably mounted on said connecting member and engageable with said locking bracket in the operating or stowed position of said legs, and cam means in said legs and means connected to said connecting member and cooperating with said cam means to retract said detent means from locking engagement with said locking bracket when said legs are pivoted toward one another.

2. In a bipod support for a firearm, means for locking the support in a stowed position relative to the firearm, said locking means comprising, latching means for removably mounting said bipod support beneath the firearm, a bracket mounted on said latching means and having a rearwardly extending projection, a connecting member pivotally mounted at one end to said bracket, a leg unit pivotally mounted on the other end of said connecting member, a sleeve member slidably mounted over said connecting member, detent means projecting up from the top of said sleeve member and arranged to fit behind said bracket projection when said connecting member is pivoted rearwardly, and spring means in said sleeve member for continually urging contact of said detent means against the rear face of said bracket behind said bracket projection thereby releasably locking said leg unit in a stowed position with respect to the firearm.

3. In a bipod support for a firearm, means for locking the support in one of a plurality of operating positions, said locking means comprising, latching means for removably mounting said bipod support beneath the firearm, a bracket mounted on said latching means and having a plurality of notches on the underside thereof, a connecting member pivotally mounted at one end to said bracket, a leg unit pivotally mounted on the other end of said connecting member, a sleeve member slidably mounted over said connecting member, a detent means projecting up from the top of said sleeve member and arranged to fit into said notches, and spring means in said sleeve member for urging said detent means into either of said notches when pivoted into alignment therewith, all adapted and arranged whereby said leg unit

is releasably locked in an operating position with respect to the firearm.

4. In a bipod support for a firearm, a pair of legs arranged to pivot so as to form a divergent angle therebetween, pivot means for swinging said legs between an inoperative stowed position and an operative position wherein said legs are substantially at right angles to the longitudinal axis of the firearm, a sleeve member slidably mounted on said pivot means, spring-biased detent means projecting up from the top of said sleeve member, and a locking bracket pivotally mounted on one end of said pivot means, said bracket having a plurality of notches on the underside thereof and a rearwardly extending projection, said notches disposed at varying positions from the pivot point of said pivot means and said locking bracket and arranged to engage said detent means whereby said legs are maintained in a plurality of operating positions of varying elevations with respect to the firearm, said projection arranged to extend in front of said detent means for releasably locking said legs in the stowed position.

5. In a bipod support having means for latching to a firearm, a locking bracket mounted on the latching means, a connecting member pivotally mounted at one end to said bracket, a pair of legs pivotally mounted to the other end of said connecting member and arranged for converging and diverging movement with respect to one another, each of said legs having a cam slot adjacent the top end thereof, a spring biased sleeve member slidably secured to said connecting member, a transverse pin extending through said sleeve member and arranged to extend through said cam slots, and detent means on said sleeve member arranged to engage with said locking bracket, all adapted and arranged whereby movement of said legs pivots said cam slots to cam said transverse pin for effecting movement of said sleeve member whereby said detent means are moved in and out of engagement with said locking bracket.

45 6. In a bipod support having means for latching on a firearm, a locking bracket mounted on the latching means, a connecting member pivotally mounted at one end to said locking bracket for movement in a plane parallel to the longitudinal axis of the firearm, a pair of legs pivotally mounted on the other end of said connecting member and arranged for diverging movement with respect to one another, each of said legs having a substantially V-shaped cam slot adjacent the top end thereof, said legs arranged in a side-by-side relationship whereby said V-shaped cam slots face in opposite directions, each of said cam slots having one arm terminating in an enlarged portion relative to the width thereof, said enlarged portion aligned to form an opening when said legs diverge, a sleeve member slidably secured to said connecting member, a transverse pin fixedly mounted in said sleeve member and arranged to extend through said opening formed by said enlarged cam slot ends, whereby said legs are releasably secured in the operative position.

7. In a bipod support having means for latching on a firearm, a locking bracket mounted on the latching means, said locking bracket having a rearwardly extending projection, a connecting member pivotally mounted at one end of said locking bracket and adapted for movement in a plane parallel to the longitudinal axis of the firearm, a pair of legs pivotally mounted on the other end of said connecting member adapted and ar-

ranged for converging movement in a plane substantially at right angles to the longitudinal axis of the firearm, each of said legs having a substantially V-shaped cam slot adjacent the top end thereof, said legs arranged in a side-by-side relationship whereby said V-shaped cam slots face in opposite directions and align to form a unitary track portion when said legs converge, a sleeve member slidably secured to said connecting member, a spring in said sleeve member arranged to urge said sleeve member upwardly, a transverse pin fixedly mounted in said sleeve member and arranged to extend through said cam slot unitary track portion, and detent means on the top of said sleeve member for engagement behind said bracket projection, all adapted and arranged whereby said detent means prevent movement of said legs in a plane parallel to the longitudinal axis of the firearm and the engagement of said transverse pin in said unitary track formed by said cam slots prevents movement of said legs in a plane disposed substantially at right angles to the longitudinal axis of the firearm.

8. The combination with a firearm of a bipod support comprising, latching means for removably mounting said bipod support beneath the firearm, bracket means pivotally secured to said latching means for transverse movement with respect to

the longitudinal axis of the firearm, a connecting member pivotally mounted at one end to said bracket means, spring biased detent means slidably mounted on said connecting member and arranged for locking engagement with said bracket means, a pair of legs pivotally mounted on the other end of said connecting member, and cam means in said legs and means connected to said connecting member and cooperating with said cam means for moving said detent means towards and away from said bracket means when said legs are respectively pivoted from or towards a spread-apart position.
